UNITED STATES PATENT OFFICE.

JAMES JACOBS, OF MAYSVILLE, KENTUCKY.

SCREW-PRESS.

SPECIFICATION forming part of Letters Patent No. 248,322, dated October 18, 1881.

Application filed June 13, 1881. (No model.)

To all whom it may concern:

Be it known that I, JAMES JACOBS, a citizen of the United States, residing at Maysville, in the county of Mason and State of Kentucky, have invented certain new and useful Improvements in Screw-Presses; and I do hereby declare the following to be a full, clear, and exact description of the invention, such as will enable others skilled in the art to which it applies to make and use the same, reference being had to the accompanying drawings, and to the letters or figures of reference marked thereon, which form a part of this specification.

15 My invention relates to screw-presses for packing tobacco and other like material; and it consists in the construction, adaptation, and application to a screw-shaft of an adjustable lever-nut, as will be hereinafter more fully set forth.

In the drawings, Figure 1 is a side elevation of my invention, partly in vertical section; and Fig. 2 is an enlarged transverse section of same cut through line $x-x$ of Fig. 1.

25 Passing through a fixed nut, B, which is rigidly attached to a cross beam or head, C, (shown in dotted lines, Fig. 1,) is a screw-shaft, A. A feather or key groove, a , is longitudinally cut in the screw-shaft parallel to the axis thereof. A corresponding groove is cut in an adjustable nut, D, and forms, in conjunction with groove a , a seat for key E. Lever-arms d are also constructed upon the adjustable nut D, and are each provided with a socket, into which is placed a removable lever, F. (Shown in dotted lines, Fig. 1.) The lower end of the screw-shaft rests in a socket constructed in the upper surface of a flanged presser-block, G. A set-screw, g , passes through the wall of the 30 socket, the inner end of which rests in an annular groove, b , cut in the shaft near its base. By means of this device the presser-block is relieved from the rotary movement of the shaft.

In packing tobacco or other like material in 45 barrels or boxes, and in order to keep the lever-sockets (heretofore immovably attached to the shaft) from descending below the top edge of the barrel, it has been the custom to place supplemental blocks under the presser-block 50 G as the material to be pressed sank under the pressure of the screw. When these blocks were required it was necessary to reverse the power and temporarily lift the presser-block up out of the way.

55 In my improved press the use of supplemental blocks is dispensed with, as the presser-block G continues to descend upon the yielding tobacco. The lever-nut D, carrying lever-sockets d , is made adjustable, and can be raised 60 from time to time to the requisite point by removing the key E from its seat, screwing the nut up to the desired height, and reinserting the key in the grooves a and e after the latter have been brought opposite each other.

65 Having thus fully described my invention, what I claim as new, and desire to secure by Letters Patent, is—

1. In a screw-press, the screw-shaft A, fixed nut B, and adjustable lever-nut D, substantially as described.

2. In combination with screw-shaft A, provided with groove a , the lever-nut D, provided with groove e , and key E, substantially as described.

75 3. In combination with screw-shaft A, nut B, and loosely-attached presser-block G, the adjustable lever-nut D, provided with socket-arms d , substantially as described.

In testimony whereof I affix my signature in 80 presence of two witnesses.

JAMES JACOBS.
